UNITED STATES PATENT OFFICE

165,922

MUSICAL INSTRUMENT

Benjamin F. Jay and Max Feintuch, Brooklyn,
N. Y., assignors to Magnafax Corporation, New
York, N. Y.

Application April 9, 1951, Serial No. 14,761

Term of patent 7 years

(Cl. D56—1)

To all whom it may concern:

Be it known, that Benjamin F. Jay and Max Feintuch, both citizens of the United States, residing at Brooklyn, in the county of Kings and State of New York, have invented a new, original, and ornamental Design for a Musical Instrument, of which the following is a specification, reference being had to the accompanying drawing, forming part thereof, and in which:

Figure 1 is a plan view, showing our new design;

Figure 2 is an edge view of Figure 1;

Figure 3 is an edge view opposite of Figure 2; and

Figure 4 is a plan view opposite of Figure 1.

We claim:

The ornamental design for a musical instrument, as shown.

BENJAMIN F. JAY.
MAX FEINTUCH.
